UNITED STATES PATENT OFFICE.

HENRY H. FORSYTH, OF CHICAGO, ILLINOIS, ASSIGNOR, BY MESNE ASSIGNMENTS, TO FORSYTH BROTHERS COMPANY, OF CHICAGO, ILLINOIS, A CORPORATION OF ILLINOIS.

METAL SASH.

939,407.

Specification of Letters Patent. Patented Nov. 9, 1909.

Application filed November 3, 1904. Serial No. 231,263.

To all whom it may concern:

Be it known that I, HENRY H. FORSYTH, a citizen of the United States, residing at Chicago, in the county of Cook and State of Illinois, have invented certain new and useful Improvements in Metal Sash, of which the following is a specification.

This invention relates to window sash and more especially that class in which the sash proper is made of resilient metal or other resilient material.

Furthermore, my invention provides a metal sash with a frame-engaging member yieldable laterally through substantially its entire length.

Heretofore sash have been constructed with a shallow spring metal attachment which has been in the nature of a window strip attached to the body of the sash proper. As a result the resiliency has been limited; whereas in my invention the frame-engaging member constitutes an element of the sash frame itself, instead of being a mere addition or attachment thereto.

One of the chief defects in metal sash has been a lack of suitable means for providing ready adjustability thereof. In the case of the ordinary window sash it is, of course, an easy matter to trim off the side members of the sash, so as to adjust the same to varying widths of window opening. In a metal sash this is especially difficult to do, and would be likely to involve injury and defacement of the sash.

One of the objects of my invention, therefore, is to provide a simple means for adjusting a metal sash to varying widths of window opening.

I also provide in my invention an efficient means for holding the glass in place within the metal frame whereby in case of breakage of the glass, another one may readily be put in its place. This is accomplished by employing wooden or other suitable filling strips, in association with glazing strips which may be readily applied and removed to retain the glass in position.

I also provide a simple means for joining the members of the sash to each other, without substantially disturbing the elasticity thereof.

Referring to the drawings, Figure 1 is a front elevation view of a metal sash embodying my invention; Fig. 2 is an end elevation view of one of the vertical members; Fig. 3 is a ver-

tical sectional view of the lower cross members of the sash on the line $x-x$ of Fig. 1; Fig. 4 is a modification in cross-section of the cross member in Fig. 3; Fig. 5 is a vertical section of the top cross member of the sash; Fig. 6 is a fragmentary cross-section of a modified form of a vertical member; Fig. 7 is a horizontal section of one of the vertical members of the sash; Figs. 8 and 9 are modifications of the horizontal section in Fig. 7; and Figs. 10 and 11 show two methods of finishing the ends of the vertical members in the sash so as to permit the sides thereof to yield laterally throughout their entire length.

In the drawings, 1 represents a suitable window frame or opening which may be made of wood or metal, provided with a guide or groove 26; said groove being formed by the side 23 and the strip 24, held in position by screws 25. The window sash is composed of vertical members 2, the top cross member 3 and the lower cross member 4, the vertical members or stiles 2 being made of elastic or resilient material, such as steel. It will be noted that 4 is formed at its lower edge with an incline, as shown in Fig. 2; to conform it to the slant of the window sill. The members of the sash are joined at the four corners thereof by means of the reinforcing block 20, preferably of wood or other non-metallic material which is fastened to the members by the pins or rivets 21. It will be noted that the block 20 enters the vertical members only a short distance and does not prevent the latter from yielding laterally at their ends and along their outer margins. The vertical members of the sash are left open along their outer margins, which allows them to readily yield laterally of the window groove or guide.

In Figs. 10 and 11, I have shown two methods of finishing the ends of the vertical members. In Fig. 10, the ends of both of the sides are lipped over, leaving space 27, intervening therebetween, while in Fig. 11, this space occurs between the lipped over end of one side and the opposite side of the vertical members.

In Figs. 7, 8 and 9, I show several methods of providing ready adjustability of the sash for varying widths of window opening. In Fig. 7 this is done by employing two strips 10, which are shouldered at 31, where

they may bear against the outer edges of the vertical member 2, and are held in position by the brads or rivets 16. It is evident that the strips 10 may be trimmed off to accommodate the variations in window opening, and that, if desired, they may also bear against the sides of groove 26. Between the strips 10 I allow a spacing 28 to permit the sides of the vertical members to yield laterally. In Fig. 8 I show a single strip 11 with corresponding spacing 28. These strips also act as stops to prevent undue distortion or collapsing of the side of the sash frame under lateral pressure. It must be evident that instead of trimming off these strips, they might be adjusted laterally by means of the brads or rivets 16, or by means of a pin-and-slot connection between them and the vertical member of the sash. In Fig. 9 I have shown such a pin-and-slot connection in the screw 17 and slot 32. The latter is made in a metal strip 12, which can, therefore, be readily adjusted laterally of the vertical member. I have shown a means of holding the glass in position within the sash frame by providing wooden or other suitable filling strips attached to the interior sides of the vertical and cross members of the sash. This attachment may be accomplished in a number of ways, and among others in the manner I have illustrated in the drawings, in which I provide a groove 15 in the sash members in which the filling strip 6 is held in position by fitting snugly therein; or by means of the pins 14. The glass 5 is held against the filling strip 6 by glazing strip 7 and by means of the brads 13. It must be evident that the groove 15 can be formed in a various number of ways, either by bending the inner margins of the sash members back upon themselves, as in Figs. 3, 5, 7 and 9, or by providing a special grooved or channel strip and attaching same to the inner margins of the members as in Figs. 4 and 8; in which 8 is the grooved metal strip and 29 the rivets holding same to said members. In Fig. 6 I have shown a different way of forming this groove, in which there is provided a spacing 33, which allows the vertical members of the sash to yield laterally throughout its entire width. The pin 14 in this case has a slideable engagement with the sides of the vertical sash members. I wish it to be understood that I do not desire to limit the scope of my invention to the various forms or constructions herein shown; also that while I have spoken of the sash as a metal one, I desire to include in this term any material in which there is present sufficient strength and resiliency to accomplish the purpose of a yieldable sash hereinabove set forth.

I claim:

1. A window sash having transversely

yieldable frame-engaging members, each of said members having side portions with an inwardly turned end permitting transverse yielding of said member.

2. A window sash having vertical transversely yieldable frame-engaging members, each of said members having side portions with an inwardly turned end permitting transverse yielding of said member.

3. A metal sash having transversely yieldable frame-engaging members unitary with and constituting elements of the sash, each of said members comprising a pair of substantially parallel sections having an inwardly turned end and so disposed as to permit transverse yielding of said member at its end.

4. A metal sash having a permanently secured filling strip adapted to seat the glass when inserted frontwise of the opening, in combination with a detachable glazing strip securing the glass in place.

5. A metal sash having a permanently secured filling strip adapted to seat the glass when inserted frontwise of the opening, in combination with a detachable wooden glazing strip securing the glass in place.

6. A metal sash having a filling strip permanently secured thereto, in combination with a detachable glazing strip adapted to coöperate with said permanent strip to hold the glass in place within the sash.

7. A sash provided on the inner margin thereof with grooves, permanently secured filling strips in said grooves, and detachable glazing strips coöperating with said permanent strips to secure the glass.

8. A metal sash provided with grooves containing permanently secured filling strips and detachable glazing strips coöperating with said permanent strips to secure the glass.

9. A metal sash having grooves containing permanently secured wooden filling strips, and detachable glazing strips adapted to coöperate with said permanent strips to secure the glass within the sash.

10. A sash having a horizontal member and a vertical transversely yieldable frame-engaging member, and means uniting the two consisting of a connecting piece secured to said horizontal member and projecting a limited distance into said vertical member but permitting the latter to yield transversely throughout its entire length.

11. A sash having a transversely yieldable frame-engaging member integral with and constituting an element of the sash frame, said frame-engaging member being provided with an adjusting strip to accommodate the sash to varying widths of window opening.

12. A metal sash having a vertical transversely yieldable frame-engaging member integral with and constituting an element of the sash frame, and an adjusting strip se-

cured to the outer margins of said member to accommodate the sash to varying widths of window opening.

13. A metal sash having a transversely yieldable frame-engaging member integral with and constituting an element of the sash frame, and a wooden adjusting strip carried thereby adapted to accommodate the sash to varying widths of window opening.

14. A metal sash having vertical hollow metal side bars open on their outer edges, in combination with one or more wooden strips adjustably secured in said open outer edges of the side bars to adjust the sash to varying widths of window opening.

15. The combination with a frame having sash-engaging grooves, of a metal sash provided on its outer edges with wooden adjusting strips adjustable widthwise of the sash.

16. The combination with a frame having a sash-engaging groove, of a metal sash having a hollow yieldable member provided on its outer edges with an adjusting strip engaging the side of the groove.

17. The combination with a frame having sash-engaging grooves, of a metal sash having vertical yieldable members integral with and constituting elements of the sash proper, and provided with adjusting strips engaging the sides of the grooves.

18. The combination with a frame having sash-engaging grooves, of a metal sash having laterally yieldable groove-engaging members integral with and constituting elements of the sash provided with wooden strips to adjust the sash to varying widths of window opening.

19. The combination with a frame having sash-engaging grooves, of a metal sash provided on its outer edges with wooden adjusting strips lying within the same.

20. A sash having frame members made of suitably bent metal and inwardly turned on their inner edges, in combination with filling strips seated in said inwardly turned edges and supporting the glass.

21. A sash having frame members made of suitably bent metal and inwardly turned on their inner edges, in combination with 50 wooden filling strips seated in said inwardly turned edges and directly supporting the glass.

22. A sash having frame members made of suitably bent metal and inwardly turned, in combination with wooden filling strips 55 securing the glass in position.

23. A sash having frame members made of suitably bent metal and inwardly turned, in combination with filling strips seated in 60 said inwardly turned portions and supporting the glass, said filling strips at their outer edges being flush with the sides of said frame members.

24. A sash having frame members made 65 of suitably bent metal and inwardly turned,

in combination with filling strips seated in said inwardly turned portions and supporting the glass, and detachable glazing strips securing the glass in place.

25. A sash having frame members made 70 of suitably bent metal and inwardly turned, in combination with filling strips seated in said inwardly turned portions and supporting the glass, and detachable wooden glazing strips securing the glass in place. 75

26. A sash having a yieldable frame-engaging member constituting an element of the sash proper, said member being provided with an adjusting strip whereby the sash may be adjusted to varying widths of window frame, said adjusting strip permitting the said yieldable member to yield throughout its entire length. 80

27. A metal sash having vertical transversely yieldable members integral with an 85 constituting elements of the sash proper, and wooden adjusting strips permitting the sash to be adjusted to varying widths of window frame without preventing the said yieldable members from yielding throughout their entire length. 90

28. A sash having a frame member made of suitably bent metal the sides whereof are inwardly turned on one or both of their inner edges, in combination with a filling 95 strip seated between the sides of said frame member, and a glazing strip securing the glass in place.

29. A sash having a frame member made of suitably bent metal the sides whereof are 100 inwardly turned on one or both of their inner edges, in combination with a filling strip seated between the sides of said frame member and having a glass-receiving seat disposed outside of the inner edge of said 105 frame member.

30. A sash having a frame member made of suitably bent metal the sides whereof are inwardly turned on one or both of their inner edges, in combination with a non- 110 metallic filling strip seated between the sides of said frame member, and a glazing strip securing the glass in place.

31. A sash having a frame member made of suitably bent metal the sides whereof are 115 inwardly turned on one or both of their inner edges, in combination with a filling strip seated between the sides of said frame member, and a non-metallic glazing strip co-operating with said filling strip to hold 120 the glass in place.

32. A sash having a frame member made of suitably bent metal the sides whereof are inwardly turned on their inner edges, in combination with a filling strip seated between said inwardly turned edges, and a glazing strip securing the glass in place. 125

33. A sash having a frame member made of suitably bent metal the sides whereof are 130 inwardly turned on their inner edges, in

combination with a filling strip seated between the sides of said frame member, and a glazing strip securing the glass in place.

34. The combination with a casing guide, of a sash having a guide-engaging member the portion of which lying inwardly of the guide is transversely yieldable, and an adjusting strip.

35. The combination with a casing guide, 10 of a sash member engaging the guide with capacity for edgewise movement relatively thereto and having an adjusting strip engaging the guide.

36. The combination with a grooved casing guide, of a sash member entering the guide groove and having an adjusting strip engaging the guide.

37. The combination with a hollow metal sash, of an adjusting strip secured to a side 20 wall of said sash, and adjusting the sash widthwise.

38. The combination with a sash guide and a sash capable of widthwise adjustment relatively to the guide, of an adjusting 25 strip secured to a side wall of the sash and adjusting the sash widthwise.

39. The combination with a bar and hollow metal stile of a window sash, of a non-metallic connection-piece at the joint of said 30 window sash.

40. The combination with a bar and hollow transversely yieldable stile of a window sash, of a non-metallic connection-piece at the joint of said members permitting trans- 35 verse yielding of the stile.

41. The combination with a sash guide, of a hollow sash frame member having a stop adapted to permit limited transverse

yielding, but prevent distortion, of said hollow sash frame member.

42. The combination with a grooved sash 40 guide, of a hollow sash frame member engaging said groove, and a stop within said hollow sash frame member adapted to permit transverse yielding, but preventing collapsing, of said hollow sash frame member.

43. The combination with a sash guide, and a hollow metal sash frame member, of means adapted to permit limited transverse yielding, but prevent distortion, of said hollow sash frame member.

44. A metal sash having grooves containing permanently secured non-metallic filling strips, and detachable glazing strips adapted to coöperate with said permanent 55 strips to secure the glass within the sash.

45. A sash having frame members made of suitably bent metal and inwardly turned, in combination with filling strips seated in said inwardly turned portions and supporting the glass, and detachable non-metallic glazing strips securing the glass in place.

46. The combination with a sash-guide, of transversely elastic sash frame member, and an adjusting strip between the latter 65 and said guide.

47. A metal sash frame member having a groove on its inner edge, in combination with a filling strip seated in said groove and having a glass-engaging seat disposed outside of the inner edge of said frame member.
